UNITED STATES PATENT OFFICE.

EMMA O. LUNT, OF DOVER, NEW HAMPSHIRE.

DESIGN FOR A CLOTHES-PIN.

SPECIFICATION forming part of Design No. 30,186, dated February 14, 1899.

Application filed January 18, 1899. Serial No. 702,591. Term of patent 14 years.

To all whom it may concern:

Be it known that I, EMMA O. LUNT, a citizen of the United States, residing at Dover, in the county of Strafford and State of New Hampshire, have invented a new and original Design for Clothes-Pins; and I do hereby declare the following to be a full, clear, and exact description of the invention, such as will enable others skilled in the art to which it appertains to make and use the same.

My invention relates to an improved clothes-pin design, reference being had to the accompanying drawings, in which—

Figure 1 is a front elevation, and Fig. 2 is a side elevation.

The design consists of any material, such as wire, bent upon itself at the middle A, and the looped end of the doubled wire is bent over on the free ends at a a', so as to form the hook B. Starting from the point A the wires are bent inward to the points b b' and

then gradually outward to the points c c'. From the points c c' the wires are bent in the form of a semicircle over upon the portion D of the hook. The free straight ends of the wire then diverge outwardly from the points d d' and terminate in outwardly-bent hooks E E', which are in a plane at a right angle to a plane drawn through the hook B. The hooks E E' are bent over upon the portions C C' and recurve, substantially as shown in the drawings.

Having thus described my invention, what I therefore claim as new, and desire to secure by Letters Patent, is—

The design for a clothes-pin substantially as herein shown and described.

EMMA O. LUNT.
